FASTENING INSERTING MACHINE

Clyde L. Knott, Beverly, Mass., assignor to United
Shoe Machinery Corporation, Flemington, N. J.,
a corporation of New Jersey

Application March 29, 1947, Serial No. 738,095

19 Claims. (Cl. 1—27)

1

This invention relates to fastening inserting machines, and is illustrated herein as embodied in a heel seat lasting machine of the type disclosed in United States Letters Patent No. 2,420,290, granted May 13, 1947, upon the application of Augustus D. Willhauck, and adapted to secure a shoe upper in lasted relation to a shoe bottom member, such as an insole, by means of fiber pegs successively severed from strands of fiber fastening material. In machines of this type, the strand or strands of fastening material are usually supplied from a reel or reels, on which the strands are coiled up, by means of a strand feeding mechanism which serves to advance the strand or strands intermittently into a strand severing mechanism in which the fastenings, such as pegs, are severed from the strand or strands.

It is an object of the invention to provide an improved strand feeding mechanism so designed that it will insure the delivery of predetermined, uniform lengths of strand material to the strand severing mechanism without undue strain on the feeding mechanism and without excessive strand tension, liable to cause strand breakages, even though the feeding mechanism is called upon to handle simultaneously a plurality of strands, in the present example up to twenty-two strands. It is a further object of the invention to provide mechanism whereby on strand failure, i. e. strand breakage or exhaustion of strand supply, the strand feeding mechanism and other operating mechanism of the illustrated machine, such as mechanism for operating a work supporting jack, are rendered inoperative. This will prevent continued operation of the machine with less than the required number of strands presented to the strand severing and peg forming mechanism until the faulty situation has been remedied. Moreover, it is a still further object of the invention to provide mechanism operable at the will of the operator to prevent the operation of the strand feeding mechanism and fastening inserting mechanism but permit the operation of the jack actuating mechanism if, for test purposes, the illustrated machine is to run with a work piece presented thereto on the jack but without the forming and driving of fastenings.

To this end and in accordance with one feature of the invention there is provided in the illustrated machine a strand pull-off member operatively connected with the strand feeding mechanism in such a way that, on completion of a strand feeding operation, the pull-off member is caused to pull off a length of strand from the supply and to hold that length of strand taut be-

2

tween the supply and the feeding mechanism. Immediately prior to the commencement of a strand feeding operation, the pull-off member is caused to slacken the extent of strand or strands between the supply and the feeding mechanism thus greatly facilitating the operation of the latter and reducing strand breakages to a minimum.

In accordance with another feature of the invention, each strand is engaged by a spring-biased feeler which is held, by its engagement with the strand, in a normal operative position against the tension of its spring. On strand failure this feeler is adapted to act on a contact member connected to a throw-out mechanism by means of which the feed mechanism and the jack mechanism may be rendered inoperative.

In order to determine the accuracy of the position of the work piece with relation to the operating instrumentalities of the machine that act upon the work piece, it is sometimes desired to run the machine with the jack presenting the work piece in operative position but without the forming and driving of fastenings. Accordingly, the invention provides a manually controlled mechanism by means of which the jack mechanism may be disconnected from the above-mentioned throw-out member, and the throw-out member rendered operative only to stop the feeding mechanism and the fastening inserting mechanism.

These and other features of the invention will now be described in detail in connection with the drawings and will be pointed out in the appended claims.

35 In the drawings,

Fig. 1 is a view in left-hand side elevation of the upper part of a heel seat lasting machine of the above-mentioned type in which the invention is illustrated as embodied;

40 Fig. 2 is a view in front elevation of part of the mechanism illustrated in Fig. 1;

Fig. 3 is a view in left-hand side elevation of the strand feeding mechanism in its operative position;

45 Fig. 4 is a view similar to Fig. 3 but with the mechanism illustrated in its inoperative position;

Fig. 5 is a detail view in left-hand side elevation of a throw-out mechanism controlling the strand feeding and jack operating mechanisms;

50 Fig. 6 is a view in front elevation of the mechanism illustrated in Fig. 5;

Fig. 7 is a view in front elevation of manual control mechanism by means of which the operation of the strand feeding mechanism and the fastening inserting mechanism may be effected;

Fig. 8 is an angular view of the manual control mechanism illustrated in Fig. 7;

Fig. 9 is an exploded view of the mechanism illustrated in Fig. 8;

Figs. 10 and 11 are views in side elevation of the mechanism shown in Fig. 7 in different positions of adjustment;

Fig. 12 is an end view of a part of the mechanism illustrated in Fig. 8;

Fig. 13 is a view in front elevation of part of the mechanism shown in Fig. 7;

Fig. 14 is a view in left-hand side elevation, partly broken away and in cross section, of the lower part of the machine showing the jack and jack controlling mechanism;

Fig. 15 is an enlarged left-hand side view, in vertical section, of a detail of the jack controlling mechanism;

Fig. 16 is an enlarged left-hand side elevational view showing a detail of Fig. 14; and

Fig. 17 is an enlarged front elevational view showing a detail of Fig. 14.

As has been stated, the invention is illustrated herein as embodied in a heel-seat lasting machine of the type disclosed in the above-mentioned patent. Accordingly, only so much of the general organization and construction of that machine will be shown and described herein as it is necessary to refer to for an understanding of this invention. It has also been explained that the machine referred to is adapted to insert into the work presented thereto fastenings in the form of pegs which are formed in the machine from strands of fastening material, for example, fiber strands S. Thus, the illustrated machine, the same as the machine in the patent referred to, has a strand supply generally indicated at A in Figs. 1 and 2, a strand feeding mechanism generally indicated at B in Figs. 1 to 4, a strand severing and peg transferring mechanism (not shown), peg inserting mechanism (not shown), a jack, generally indicated at C in Fig. 14 adapted to support a shoe last and a shoe mounted thereon, and a jack controlling mechanism, generally indicated at D in Figs. 14 and 15, adapted to control the movements of the jack into and out of operative position. In its operative position the jack presents the heel seat portion of the shoe to the lasting mechanism (not shown), the latter mechanism including wipers and a heel end clamping band.

The illustrated machine is equipped to process simultaneously up to twenty-two fiber strands for the simultaneous insertion into the heel seat portion of the shoe of up to twenty-two fiber pegs severed from the strands. Thus, the strand supply A of the illustrated machine comprises twenty-two reels, indicated at 20 in Figs. 1 to 4. Only eleven reels are shown in Fig. 1, the other eleven reels being located behind the reels shown in that figure. Each reel carries a coil of fastening material. To support the reels in the machine, the machine frame 22 is provided with two uprights 24 connected together by a horizontal bar 26 extending through brackets 28 secured to the uprights. Similar brackets 30 are carried in uniformly spaced relation on the bar 26 and each bracket 28, 30, with the exception of the bracket 28 at the extreme right of Fig. 1, has two extensions or arms 32, on each of which two reels 20 are rotatably mounted in side by side relation. The just-mentioned bracket 28 at the extreme right of Fig. 1 has three extensions or arms 32 and thus carries six reels 20. The strands of fastening material run through suitable guiding

eyes 34 secured to the brackets 28, 30 and from there run toward the front of the machine. The entire strand supply is protected against dirt and other foreign matter that otherwise might drop into it by a cover 36 mounted on the upper ends of the uprights 24.

The mechanism proper for feeding the fiber strands which is illustrated best in Figs. 3 and 4 is substantially the same as the strand feeding mechanism of the machine disclosed in the above-mentioned patent. Briefly, the illustrated strand feeding mechanism comprises a feed roller 38 and a cooperating pressure roller 40, between which rollers the twenty-two strands of fastening material pass and which serve intermittently to advance the strands into the strand severing mechanism of the machine. The feed roller 38 is preferably a solid unyieldable member provided with twenty-two grooves adapted to receive the twenty-two strands, whereas the pressure roller 40 is made of a yielding material such as rubber. The feed roller 38 is secured on a shaft 42 rotatably mounted in a bracket 44 secured to the machine frame. There are mounted on the shaft 42, as fully disclosed in the patent referred to, two oppositely operating Horton clutches. The outer driving sleeve of the first clutch is indicated at 46 in Figs. 2, 3 and 4 and, as will be described, it is oscillated so as to impart to the shaft 42 and the feed roller 38 an intermittent rotation in one and the same direction. The second Horton clutch, as also fully disclosed in the patent referred to, merely serves to lock the shaft 42 on reverse rotation of the sleeve 46 of the first clutch by the driving mechanism to be described.

The pressure roller 40 is secured on a shaft 48 rotatably mounted in a swingable frame or bracket 50. Gearing 49 (Fig. 2) is provided to transmit the rotation of the shaft 42 to the shaft 48, the arrangement being such that the two rollers 38 and 40 rotate at about the same peripheral speed. The bracket 50 (Figs. 2, 3 and 4) is hinged on a shaft 52 which is secured in the lower end of the bracket 44. A coupling pin 54 is pivotally mounted on a shaft 56 secured in the upper portion of the bracket 44 and normally lies in a grooved portion provided in the upper end of the bracket 50 and is held in that position by a thumb nut 58 threaded onto the pin 54 and abutting the bracket 50. Thus, the pressure of the roller 40 against the roller 38 may be adjusted by the manipulation of the thumb nut 58.

The already-mentioned mechanism for actuating the strand feeding mechanism will now be described. The above-mentioned outer driving sleeve 46 of the first Horton clutch has a lug 60 (Figs. 3 and 4) with which is pivotally connected the forward end of a reciprocating actuating member in the form of a link 62. The link 62 carries at its rearward end a headed pin 64, the head of which is held in a T-shaped guideway 66 provided in a substantially vertical rocking lever 68. As will be described, the pin 64 is adjustable along the guideway 66 so as to vary the length of feed movement imparted to the strands S. The lever 68 is secured to a shaft 70 rotatably mounted in a lug 72 provided on the machine frame 22. Threaded onto the pin 64 is a thumb nut 74 by means of which the pin 64 may be caused to bind in the guideway 66 and thus to maintain its position of adjustment therein. On the other hand, upon loosening the thumb nut 74 the pin 64 may be adjusted along the guideway 66 with relation to the shaft 70, thereby varying the effective length of the rocking lever.

68 and thus the throw of the link 62 and consequently the length of feed movement imparted to the strands S.

For the purpose of rocking the lever 68 there is pivotally secured to it at 78 a driving rod 76 (Figs. 1, 3 and 4). The rearward end portion of the driving rod 76 is threaded into a turn buckle 80, through the other end of which there is slideable a rod 82. A spring 84 is mounted on the rod 82 between a fixed collar 86 and the turn buckle 80 and serves to transmit the motion of the rod 82 toward the right of Fig. 1 to the driving rod 76. As in the machine of the above-mentioned patent, the rod 82 is actuated by a bell-crank lever 88 pivotally secured on the machine frame and connected by means of a vertical rod 90 to a slide (not shown) which is mounted for reciprocation in the machine frame and which is provided with a cam follower (not shown), the cam follower being actuated by a cam (not shown) mounted upon the drive shaft (not shown) of the machine. As will be seen, reciprocation of the rod 90 causes reciprocation of the rod 76 to actuate the above-described strand feeding mechanism. The length of feed movement imparted to the strands S may be regulated by adjusting the headed pin 64 along the guideway 66 as described. The strands after leaving the feed roller 38 and pressure roller 40 are received in guiding tubes 92 which conduct the strands into the above-mentioned strand severing and peg transferring mechanism.

To assist the above-described strand feeding mechanism in its operation there is provided a pull-off mechanism illustrated best in Figs. 3 and 4. The pull-off mechanism comprises a pull-off roller 94 over which the twenty-two strands S of fastening material pass. The roller 94 engages the strands at a location between the strand supply or reels 20 and the strand feeding mechanism, in particular, the rolls 38 and 40. The pull-off roller 94 is mounted on a movable support in the form of an arm 96 which is pivotally secured at 98 to the bracket 28 at the extreme right of Fig. 1. The free end of the arm 96 is forked and has pivotally secured thereto a trunnion block 100 which is bored vertically to receive a rod 102 held in position by a nut 104 engaging the upper extremity of the rod and resting against the top face of the trunnion block. The nut 104 is secured against rotation by a lock nut 106. The rod 102 is pivotally secured at its lower end to an arm 108 which is secured upon a shaft 110 mounted for rotation in a bracket 112 secured to the machine frame. A spring 114 is mounted on the rod 102. The upper end of the spring 114 abuts the trunnion block 100 and its lower end rests against a washer 116 held on the rod 102 by nuts 118. It will be seen, therefore, that the spring 114 normally serves to maintain the pull-off roller 94 yieldingly in its uppermost position in which the roller 94 holds taut the extents of fiber strands between the strand supply and the strand feeding mechanism. Secured to the shaft 110 is also a rearwardly extending arm 120 which is pivotally connected to a downwardly extending link 122. The link 122 is pivotally connected to a lug 124 which is part of the outer driving member 46 of the above-mentioned first Horton clutch on the shaft 42 of the strand feeding mechanism. The arrangement is such that on forward movement of the above-mentioned reciprocating link 62, during which the feed roller 38 is rotated to advance the fiber strands, the just-mentioned lug 124 is rotated in a clock-

wise direction, as viewed in Figs. 3 and 4, with the result that the link 122 is elevated. The shaft 110 is rotated in a clockwise direction, as viewed in Fig. 3, by reason of the rotation of the arm 120 in the same direction due to the elevation of the link 122. This, of course, also causes a clockwise rotation of the arm 108 as a result of which the rod 102 is lowered, thereby positively lowering, through the agency of the nut 104 and trunnion block 100, the pull-off roller 94. In consequence of the lowering of the pull-off roller 94 the extents of fiber strands between the strand supply and the strand feeding mechanism are slackened. Thus, the task of the strand feeding mechanism in advancing the twenty-two fiber strands is considerably facilitated and the danger of strand breakage, imminent by the sudden application of considerable tension to the fiber strand, is mitigated. As pointed out, the slackening of the strands by the pull-off mechanism occurs simultaneously with the beginning of the strand feeding operation. If after a feeding operation the link 62 is returned toward the left of Fig. 3 into its initial position the lug 124 is rotated in a counter-clockwise direction with the result that the shaft 110 is rotated in a counter-clockwise direction elevating the rod 102 and collar 116 secured thereon, as a result of which elevation the pull-off roller 94 is yieldingly moved back into its uppermost position through the agency of the spring 114. The timing of these movements is such that the slackening of the strands by the pull-off mechanism occurs quickly and that the actual strand feeding operation also only occupies a minor portion of one cycle of operations of the machine. On the other hand, however, the return of the pull-off roller 94 into its initial strand tensioning position consumes a considerable portion of a cycle of operations.

During this return of the pull-off roller 94 into its initial position it causes a new extent of strand or strands to be pulled off the reels 20 relatively slowly and this new extent of strand is, so to speak, held in readiness by the pull-off member 94 for the next strand feeding operation. Accordingly, the strand feeding mechanism proper is relieved from the task of actually pulling the strands off of the reels. As stated, the pulling off is effected by the roller 94 in a manner much slower than could be effected by the strand feeding mechanism, thus also preventing the reels 20 from overturning in which case too much strand would be unreeled.

It nevertheless may occur from time to time that one or several of the twenty-two strands will break. Moreover, it may happen that the coil of strand on one of the reels 20 becomes exhausted. In the following these occurrences are generically designated as strand failure. Strand failure results in the insertion into the heel seat portion of the shoe of a less number of pegs than is required which, of course, is not desirable. To bring about, therefore, an automatic stopping of the machine on strand failure, the following mechanism, illustrated best in Figs. 3 and 4, is provided. There are pivotally mounted on the above-described shaft 56 in the bracket 44, twenty-two plate-like feelers 126, each of which is provided with a rearwardly extending screw eye 128 to which the upper end of a vertical spring 130 is secured. The lower end of the spring is attached to the bracket 44. The twenty-two feelers 126 are so arranged that a substantial portion of each feeler is located behind each strand S and is held by the spring

130 in engagement therewith. Located in front of the feelers 126 and extending crosswise over the twenty-two fiber strands is a contact member 132 which has at opposite ends upwardly extending portions by means of which it is pivotally mounted on the shaft 56. The contact member is so arranged that it engages or is closely spaced from the twenty-two strands in front of the portions thereof which are engaged by the feelers 126. Accordingly, the twenty-two strands S extend between the feelers 126 and the contact member 132 and hold the feelers in their normal operative position against the tension of the springs 130, each of which tends to swing out its respective feeler 126 in a counter-clockwise direction as viewed in Fig. 3. Thus, a feeler 126 may swing out as just described only upon failure of the strand S extending between it and the contact member 132. Such a condition is illustrated in Fig. 4 of the drawings. The swinging out of one of the feelers 126 causes that feeler to contact the member 132 and also rotate that member in a counter-clockwise direction about the shaft 56. This movement of the contact member 132 is utilized in automatically stopping or throwing out of operation the strand feeding mechanism.

This automatic throw-out mechanism will now be described. It is illustrated in Figs. 3, 4, 5 and 6 of the drawings. The throw-out mechanism, of course, is normally inoperative and is adapted automatically to throw out the operation of the strand feeding mechanism upon strand failure. The above-mentioned contact member 132 is connected by a rearwardly extending link 134 to an arm 136 which constitutes part of the throw-out mechanism. The core of the throw-out mechanism is a shaft 138 fixed in the machine frame. To this end the frame 22 of the machine has secured to it a split bearing 140 (Figs. 5 and 6) in which a portion of the shaft 138 is mounted and which is tightened, to bind the shaft, by a draw bolt 142 secured in position by a nut as is customary. Rotatably mounted on the freely extending outer end of the shaft 138 is a three-armed normally inoperative throw-out member 144. The member 144 has a normally upwardly extending arm 146 (Fig. 5) on which is provided a laterally extending sleeve 148 (Fig. 6). Rotatably mounted in the sleeve is a pin 150 to one end of which the above-mentioned arm 136 is secured. The pin 150 is provided about halfway between its ends and at its lower portion with a recess 152 which extends transversely to the longitudinal axis of the pin and the top wall of which is somewhat curved, as best shown in Fig. 5, substantially along a diameter of the pin. A corresponding recess or hole is provided in the sleeve 148. In the normal position of the parts, that is to say, when the throw-out mechanism is inoperative, and this position is illustrated in Fig. 5 in full lines, the recess 152 is so located that it does not impede the free movement through it of a pusher 154 which is secured on a segment-shaped member 156, the hub 158 of which is rotatably mounted on the shaft 138 between the hub of the throw-out member 144 and the split bearing 140 (see Fig. 6). The segment 156 is rocked during the operation of the machine by means of a link and lever connection to the strand feeding mechanism. This link and lever mechanism comprises a link 160 pivotally secured by a pivot screw 162 to the segment 156. The other end of the link is pivotally connected by means of a screw 164 to an arm 166 which is

secured on the rock shaft 70 of the mechanism for actuating the strand feeding mechanism. As above described, on strand failure the feeler or feelers 126 previously engaging the strand or strands which have become broken or exhausted are swung out by their respective springs 130 with the result that the contact member 132 also is swung out as illustrated in Fig. 4 of the drawings. This results in a forward movement of the link 134 and in a counter-clockwise rotation, as viewed in Fig. 3 or 5, of the arm 136. This rotation of the arm 136 causes counter-clockwise rotation of the pin 150 within the sleeve 148 so that the position of the above-described recess 152 in the pin 150 is changed with relation to the path of movement of the pusher 154. Of course, this rotation of the pin 150 and the change in position of the recess 152 can take place only when the pusher 154 is not located within the pin 150 or, in other words, when the segment-shaped member 156 is substantially at the left hand end of its path of movement, as viewed in Fig. 5. When after the rotation of the pin 150, as described, the segment-shaped member 156 is again moved toward the right of Fig. 5 the pusher 154 mounted thereon is caused to strike against the pin 150 after having moved through the above-mentioned corresponding recess or hole provided in the sleeve 148. As a result the pusher 154 moves the pin 150 and with it the throw-out member 144 into the position indicated in dotted lines in Fig. 5. Thus, the throw-out member 144 is rotated in a clockwise direction from the full line position into the dotted line position of Fig. 5. This also results in a locking of the strand feeding mechanism as will be described. To this end there is pivotally connected to the downwardly extending arm 168 of the throw-out member 144 a downwardly and forwardly extending rod 170 which passes through a trunnion block 172 rotatably secured in the forked end of an arm 174 secured on a shaft 176 mounted for rotation in a bearing provided in the machine frame. Secured on the shaft 176 is also an upwardly extending latch arm 178 which is adapted to cooperate with a latch 180 secured on the shaft 70. The rod 170 carries on it a spring 182 which is confined between the trunnion block 172 and a washer 184 (Figs. 3 and 4) held on the lower end portion of the rod 170 by lock nuts 186. It will be seen, therefore, that on clockwise rotation of the throw-out member 144 into the dotted line position of Fig. 5 by the pusher 154 the spring 182 is active to rotate the arm 174 in a counter-clockwise direction as viewed in Fig. 5 as a result of which the latch arm 178 is brought into engagement with the latch 180. Thus, the shaft 70 is locked against rotation and continued motions of the rod 170 are absorbed by the spring 182. It will be understood that the locking of the shaft 70 results in the strand feeding mechanism being rendered inoperative.

Moreover, since it is desirable on strand failure also to render the jack operating mechanism inoperative, the throw-out member 144 has a third arm 188 (Fig. 5) provided with a lateral extension shown in Fig. 6 to which is pivotally secured a rod 190. The rod 190 extends downwardly through a lug 192 provided on the machine frame and carries a spring 194 which is confined between the lug 192 and a fixed collar on the rod 190. At its lower end the rod 190 is connected by means of mechanism to be described with the jack control mechanism shown in Figs. 14 through

17. It will be readily apparent from an examination of Fig. 14 that the jack C and its controlling mechanism D are substantially the same as the fluid operated jack and jack control mechanism disclosed in United States Letters Patent No. 2,085,755, granted July 6, 1937, on an application of J. C. Jorgensen. As disclosed and illustrated in that patent (Fig. 3), swinging movement of a latch 186 out of latching engagement with a bar 176 results in the rendering of the jack control mechanism inoperative and it is with the equivalent of the latch 186 that the rod 190 of the present machine is indirectly connected, as will later be described in more detail.

It is sometimes desired to operate the illustrated machine for test purposes with the jack in operative position and with a shoe thereon but without the insertion of fastenings into the shoe. This, for example, is done when at the beginning of the operation upon a new run of shoes of sizes or styles different from those previously operated upon, the selected size and position of the wipers with relation to the heel seat portion of the shoe are to be tested. This means that during such test operation the strand feeding mechanism and the fastening inserting mechanism should be inoperative but that the jack control mechanism should be operative to permit the jack to locate the work in operative position with relation to the wipers. This end is served by the manually operated control mechanism which is illustrated in detail in Figs. 7 to 13, inclusive. This mechanism includes a bearing sleeve 196 (best shown in Fig. 9). The sleeve 196 is fixed in a bore 198 (Fig. 7) provided in the machine frame 22, the sleeve 196 extending outwardly from the frame 22 a certain distance. Rotatably mounted on the outwardly extending portion of the sleeve 196 are two control members 200 and 202 which, as will be presently described, are normally connected together so that movement of one will result in movement of the other. The above-mentioned rod 190 connected to the throw-out member 144 is pivotally connected at its lower end to a lug 204 extending radially from the control member 200. The other control member 202 has a radial lug 206 which is positioned in diametrically opposite relation to the lug 204. To the lug 206 is pivotally connected a downwardly extending cable 208 which is connected at its lower end to the fluid operated jack control mechanism D, in particular, to the already described latch 260, corresponding to the latch 186 disclosed in the above-mentioned patent to Jorgensen. Since the two control members 200 and 202 are normally coupled together they act as, and may be considered to be, a two-armed lever. Accordingly, on operation of the throw-out member 144 above-described, in particular, on movement of that member into the dotted line position of Fig. 5, the strand feeding mechanism is locked and the rod 190 is moved downwardly, rotating the two control members 200 and 202 in a counter-clockwise direction, as viewed in Fig. 10, into a position indicated in Fig. 11, thereby pulling up on the cable 208 to render the jack controlling mechanism inoperative in the following manner. Referring to Figs. 14 through 17, it will be seen that the cable 208 extends downwardly through a tubular guide 262 which is secured at its lower opening to a fixed casting 264. The lower portion of the cable 208 extending downwards past the opening in the guide passes through a loose fitting bore 266 in a forwardly extending arm 268 which, with the latch portion 260, forms a bell

crank lever pivotally mounted upon a horizontal pin 270. The lower extremity of the cable 208 is fastened to a lifting plug 272 suspended between the cable and an upwardly yielding spring 274. 5 A plunger bar 276, which is equivalent to the before-mentioned bar 176 of the Jorgensen patent, is positioned within a vertical slideway 278 in a fixed bracket 280. The bar 276 is normally held in the depressed position, as depicted in Fig. 15, 10 by the downward force of a return spring 282, and the bar may be elevated to activate the jack by a thrust rod 284 which is treadle operated. The vertical travel of the bar 276 is limited by a fixed stop pin 286 which protrudes into a guide 15 groove 288 cut in the bar. The upper portion of the bar 276 is slidably journaled through a movable yoke 290 to which the latch 260 is anchored by the pivot pin 270; thus when the latch is engaged with a notch in the bar the yoke 290 will be 20 elevated when the treadle is operated. A pressure valve (not shown) for operating the jack is directly connected to an arm 292 extending laterally from the yoke 290. The latch 260 is normally held in engagement with the bar 276 by the downward force of a spring 294 anchored at its lower extremity to the outer end of the stop pin 286. From the foregoing it will be seen that the jack operating valve may normally be opened by the elevation of the treadle operated plunger bar 276, 25 however, upon strand failure the cable 208, as above described, will be pulled upward by the counterclockwise movement of the rotary control member 202, so that the lifting plug 272 will strike the lever arm 268 swinging the latch 260 30 counter-clockwise out of engagement with the notch in the bar 276 so that the elevation of the bar by the treadle will be ineffective to lift the yoke 290 and open the jack operating valve. The machine cannot be restored to operative condition 35 unless a new strand S is threaded between its feeler 126 and the contact member 132 and the contact member is manually pushed inwardly of the machine, thereby causing a resetting of the throw-out member 144 into its normally inoperative position illustrated in full lines in Fig. 40 45 5. This, of course, results in the unlocking of the strand feeding mechanism by the separation of the latch arm 178 from the latch 180 and in the elevation of the rod 190 by which the jack controlling mechanism again is rendered operative 50 by the reengagement of the latch 260 with the bar 276.

However, as stated, a different state of affairs has to prevail when the machine is run for test purposes with the strand feeding mechanism and the fastening inserting mechanism inoperative, but with the jack controlling mechanism operative. This necessitates, first of all, a separation of the control members 200, 202 so that throwing out the strand feeding mechanism no longer affects the operation of the jack. The control member 202 carries a locking pin 210, best shown in Fig. 9, which extends parallel to the axial direction of the bearing sleeve 196 and which is adapted to enter into a hole 211 provided in the control member 200. In the normal operation of the machine the members 200, 202 are thus locked together by the pin 210 with the results described. The pin is controlled by a hand wheel 212 having a stem portion 214 and on the stem portion and integral with it a cup-shaped portion 216, the bottom of the portion 216 being adjacent to the stem. The open end or brim of the cup-shaped portion 216 has a radial flange 218 extending 65 inwardly therefrom and the locking pin 210 has

a rabbeted portion 220 which fits over the flange 218. The hand wheel 212 and the parts integral therewith are secured upon a rotatable and longitudinally movable bolt 222 which extends from the hand wheel 212 inwardly through the bearing sleeve 196 and thence further inwardly through the bore 198. Inwardly of the bearing sleeve 196 the bolt 222 has a portion which carries a spring 224 confined between the inner end of the bearing sleeve 196 and a shoulder 226 of the bolt. The spring 224 thus tends to pull the bolt 222 inwardly. Outward movement of the hand wheel 212 and thus of the bolt 222 in the axial direction of the bolt and against the tension of the spring 224 causes the locking pin 210 to be withdrawn from the control member 200 and accordingly causes the members 200 and 202 to become disconnected from each other.

After unlocking or disconnecting the control members 200 and 202 by drawing the bolt 222 slightly outward, the hand wheel 212 when turned in a counterclockwise direction as viewed in Fig. 10, will rotate the control member 200 in the same direction, without effecting any movement of the control member 202, thereby to pull down the rod 190 and to throw out the strand feeding mechanism by rotation of the throw-out member 144 into the dotted line position of Fig. 5 but to leave operative the jack controlling mechanism. To cause such rotation of the control member 200 the latter is provided with a pin 228 (Fig. 9) outwardly extending through a recess 230 cut into the periphery of the control member 202 and also extending through a cut-out portion or recess 232, best shown in Fig. 12, provided in the flange 218 of the hand wheel 212. As seen in Fig. 12 the upper side of the pin 228 normally abuts one end of the recess 232 and this pin extends outward sufficient to still abut within the recess 232 while the hand wheel is withdrawn, so that on rotation of the hand wheel 212 in a counterclockwise direction as viewed in Fig. 10 the pin 228 moves the control member 200 along with the hand wheel 212. Due to the provision of the recess 230, this movement of the pin 228 does not affect the control member 202. This, of course, causes the spring 194 to be loaded which then will tend to return the parts into their initial position unless they are locked in their new position of adjustment. Accordingly, after the rotation of the hand wheel 212 as described, the hand wheel again is moved axially, this time inwardly with the result that the pin 228 enters a hole 234 (Figs. 8 and 9) provided in the bottom of the cup-shaped portion 216 of the hand wheel 212. As will be described, the hand wheel 212 may be locked in whatever position of adjustment it happens to be. Inward movement of the hand wheel 212 causes inward movement of the locking pin 210, and entrance of the pin 210 in a hole 236 provided in the control member 200 adjacent to the hole 211 and spaced from the latter hole a distance corresponding to the extent of rotation of the control member 200 by the hand wheel 212. It will be understood that the rotation of the hand wheel is with relation to the locking pin 210 during which rotation the flange 218 moves through the rabbeted portion 220 of the locking pin 210. Entrance of the pin 210 in the hole 236 locks the control member 202 in its operative position so that the jack operating mechanism D cannot be rendered inoperative by mistake.

Inward axial movement of the hand wheel 212, as stated, displaces the bolt 222 inwardly, the inward movement of the bolt being assisted by the

tensioned spring 224. As is fully disclosed in the above-mentioned patent to Willhauck, the machine disclosed therein has a plunger 144 which serves to operate the fastening inserting mechanism. The machine illustrated herein has a corresponding plunger 238 (Fig. 7) which serves to operate the fastening inserting mechanism in similar fashion by moving downwardly from the position indicated in Fig. 7. This plunger 238, 10 the same as the plunger 144 of the machine disclosed in the above-mentioned patent to Willhauck, has a recess 240 which, when the plunger 238 is in its uppermost position, is located opposite the bore 198 in which the bolt 222 is movable. 15 Accordingly, inward movement of the bolt 222, as described, causes the bolt to enter the recess 240 and to lock the plunger 238 in its uppermost position, thereby rendering the fastening inserting mechanism inoperative.

For the purpose of holding the hand wheel 212 in either of its two positions of adjustment the cup-shaped portion 216 has in its side wall two diametrically opposite, axially extending notches 242 (Figs. 9 and 12) into which may enter a tongue 244 extending axially outwardly from a plate 246 integral with the outer end of the bearing member 196 and apertured to permit passage therethrough of the bolt 222. The tongue 244 enters the notch 242 when the hand wheel 212 is in its normal position in which the control members 200, 202 are locked together and are free to rotate as a unit about the bearing sleeve 196 (see Fig. 8). Thus it will be seen also that the hand wheel 212, before it can be rotated in a counter-clockwise direction as viewed in Fig. 10, has to be pulled out first as described, not only to unlock the control members 200, 202, but also to move the cup-shaped member 216 away from the fixed tongue 244 until the latter is clear of the notches 242. After the rotation of the hand wheel 212 as described it is, as already stated, again moved inwardly assisted by the spring 224, to lock the fastening inserting mechanism by causing the bolt 222 to enter the recess 240 of the plunger 238. However, the bolt 222 to this end has to move inwardly further than it normally is permitted to move by the axial extent of the notches 242. Accordingly, there is provided in the member 216 adjacent to the notches 242 a second pair of diametrically opposite, axially extending notches 248 of considerably longer extent than the notches 242. The notches 248 are so located that on completion of the rotation of the hand wheel 212 in a counterclockwise direction, as viewed in Fig. 10, to throw out the strand feeding mechanism the notches 248 are opposite the stationary tongue 244 which, on ensuing inward axial movement of the hand wheel 212, enters the notches 248 to hold the hand wheel in its new position of adjustment, the notches 248 permitting the bolt 222 to move inwardly far enough to enter the recess 240 of the plunger 238.

After the completion of the test run of the machine the operative condition of the machine is restored by a reverse manipulation of the hand wheel 212. In particular, the hand wheel first is moved axially outwardly to withdraw the cup-shaped member 216 from the tongue 244 and to withdraw the bolt 222 from the recess 240 of the plunger 238, thereby unlocking the fastening inserting mechanism. Then the hand wheel 212 is rotated in a clockwise direction as viewed in Fig. 11 with the result that the control member 200 is rotated in a clockwise direction back into its initial position under the action of the loaded

spring 194, this back rotation of the control member 200 being permitted by the pin 210 which, as a result of the first-described outward movement of the hand wheel 212, also was withdrawn from the hole 236 of the control member 200. The hand wheel is rotated in clockwise direction as viewed in Fig. 11 until the notches 242 are opposite the tongue 244, whereupon the hand wheel 212 again is moved inwardly in the axial direction, thereby causing the tongue 244 to enter the notches 242 and also causing the locking pin 210 to reenter the hole 211 of the control member 200. This again locks the hand wheel 212 and also locks the control members 200 and 202 together for free rotary movement as a unit about the bearing sleeve 196.

Having thus described my invention, what I claim as new and desire to secure by Letters Patent of the United States is:

1. In a strand feeding mechanism, the combination with a rotary reel on which the strand is wound up and strand feeding means, of a strand feeler held in a normal position by engagement with one side of the strand, means adapted to displace the feeler out of its normal position upon strand failure, a movable contact member normally held on the opposite side of the strand in juxtaposition with the feeler and adapted to be contacted and moved on displacement of the feeler, and connections between the contact member and the strand feeding means adapted to render the strand feeding means inoperative on displacement of the feeler out of its normal position.

2. In a strand feeding mechanism, the combination with a rotary reel on which the strand is wound up and strand feeding means, of a strand feeler held in a normal position by engagement with one side of the strand, a spring adapted to move the feeler out of its normal position upon strand failure, normally inoperative mechanism adapted to throw out the strand feeding means, a member normally held on the opposite side of the strand in juxtaposition with the feeler and adapted to be contacted by the feeler on movement out of its normal position, and a connection between said member and the normally inoperative mechanism, the connection being adapted, upon movement of the feeler out of its normal position, to render said mechanism operative to throw out the strand feeding means.

3. In a strand feeding mechanism, the combination with a rotary reel on which the strand is wound up and strand feeding means, of a strand engaging feeler located between the reel and the strand feeding means and held in a normal position by engagement with one side of the strand, a pivot upon which the feeler is mounted for swinging movement into and out of its normal position, a spring engaging the feeler and tending to swing it out of its normal position, a movable contact member on the opposite side of the strand located adjacent to the feeler with the strand separating the feeler and the contact member when the feeler is in its normal position, a normally inoperative throw-out member adapted to render the feeding means inoperative, and a link connecting the contact member with the throw-out member, the link being adapted, upon movement of the feeler out of its normal position due to strand failure, to render the throw-out member operative to throw out the strand feeding means.

4. In a fastening inserting machine, the combination with a work supporting jack movable

into and out of an operative position, jack controlling means and mechanism for preventing a strand of fastening material, said mechanism including a strand supporting reel and strand feeding means, of a strand feeler held in a normal position by engagement with the strand, means adapted to displace the feeler out of its normal position upon strand failure, a movable contact member adapted to be moved on displacement of the feeler, and connections between the contact member and the jack controlling means adapted to render the jack inoperative on displacement of the feeler out of its normal position.

5. In a fastening inserting machine, the combination with a work supporting jack movable into and out of an operative position and mechanism for presenting a strand of fastening material, said mechanism including a strand supporting reel and strand feeding means, of a strand feeler held in a normal position by engagement with the strand, a spring adapted to move the feeler out of its normal position upon strand failure, normally inoperative mechanism adapted to render the jack inoperative, a member adapted to be contacted by the feeler on movement out of its normal position, and a connection between said member and the normally inoperative mechanism, the connection being adapted, upon movement of the feeler out of its normal position, so to act on said mechanism as to render the jack inoperative.

6. In a fastening inserting machine, the combination with a work supporting jack movable into and out of an operative position and mechanism for presenting a strand of fastening material, said mechanism including a strand supporting reel and strand feeding means, of a strand engaging feeler located between the reel and the strand feeding means and held in a normal position by engagement with the strand, a pivot upon which the feeler is mounted for swinging movement into and out of its normal position, a spring engaging the feeler and tending to swing it out of its normal position, a movable contact member located adjacent to the feeler with the strand passing between the feeler and the contact member when the feeler is in its normal position, a normally inoperative throw-out member adapted to render the jack inoperative, and a link connecting the contact member with the throw-out member, the link being adapted, upon movement of the feeler out of its normal position due to strand failure, so to act on the throw-out member as to render the jack inoperative.

7. In a fastening inserting machine, the combination with a work supporting jack movable into and out of an operative position and mechanism for presenting a strand of fastening material, said mechanism including a strand supporting reel and strand feeding means, of a strand engaging feeler located between the reel and the strand feeding means and held in a normal position by engagement with the strand, a pivot upon which the feeler is mounted for swinging movement into and out of its normal position, a spring engaging the feeler and tending to swing it out of its normal position, a movable contact member located adjacent to the feeler with the strand passing between the feeler and the contact member when the feeler is in its normal position, a normally inoperative throw-out member adapted to render the jack inoperative, and a link connecting the contact member with the throw-out member, the link being adapted, upon movement of the feeler out of its normal position

due to strand failure, to cause the strand feeding means to operate the throw-out member so as to render the jack inoperative.

8. In a fastening inserting machine, the combination with a work supporting jack movable into and out of an operative position and mechanism for presenting a strand of fastening material, said mechanism including a strand supporting reel and strand feeding means, of a strand feeler held in a normal position by engagement with the strand, means adapted to displace the feeler out of its normal position upon strand failure, a movable contact member adapted to be moved on displacement of the feeler, normally inoperative control means adapted, on operation, to render both the strand feeding means and the jack inoperative, and a connection between the contact member and the control means, the connection being adapted, on movement of the feeler out of its normal position, to cause an operation of the control means so as to render both the strand feeding means and the jack inoperative.

9. In a fastening inserting machine, the combination with a work supporting jack movable into and out of an operative position, jack controlling mechanism, and mechanism for presenting a strand of fastening material, the latter mechanism including a strand supporting reel and strand feeding means, of a throw-out mechanism for rendering the strand feeding means inoperative, a connection between the throw-out mechanism and the jack controlling mechanism, said connection including two movable control members connected to the throw-out mechanism and the jack controlling mechanism respectively, and a coupling adapted to lock the two members together so that operation of one results in operation of the other.

10. In a fastening inserting machine, the combination with a work supporting jack movable into and out of an operative position, jack controlling mechanism, and mechanism for presenting a strand of fastening material, the latter mechanism including a strand supporting reel and strand feeding means, of a throw-out mechanism for rendering the strand feeding means inoperative, a connection between the throw-out mechanism and the jack controlling mechanism, said connection including two movable control members connected to the throw-out mechanism and the jack controlling mechanism respectively, a coupling adapted to lock the two members together so that operation of one results in operation of the other, and means for disconnecting said two members.

11. In a fastening inserting machine, the combination with a work supporting jack movable into and out of an operative position, jack controlling mechanism, and mechanism for presenting a strand of fastening material, the latter mechanism including a strand supporting reel and strand feeding means, of a throw-out mechanism for rendering the strand feeding means inoperative, a connection between the throw-out mechanism and the jack controlling mechanism, said connection including two movable control members connected to the throw-out mechanism and the jack controlling mechanism respectively, a coupling adapted to lock the two members together so that operation of one results in operation of the other, and operator controlled means for disconnecting said two members and then moving the member connected to the throw-out mechanism so as to render the strand feeding means inoperative.

12. In a fastening inserting machine, the combination with a work supporting jack movable into and out of an operative position, jack controlling mechanism, and mechanism for presenting a strand of fastening material, the latter mechanism including a strand supporting reel and strand feeding means, of a throw-out mechanism for rendering the strand feeding means inoperative, a connection between the throw-out mechanism and the jack controlling mechanism, said connection including two movable control members connected to the throw-out mechanism and the jack controlling mechanism respectively, a coupling adapted to lock the two members together so that operation of one results in operation of the other, operator controlled means for disconnecting said two members and then moving the member connected to the throw-out mechanism so as to render the strand feeding means inoperative, and means for locking the last mentioned member after it has been so moved by the operator controlled means.

13. In a fastening inserting machine, the combination with a work supporting jack movable into and out of an operative position, jack controlling mechanism, and mechanism for presenting a strand of fastening material, the latter mechanism including a strand supporting reel and strand feeding means, of a throw-out mechanism for rendering the strand feeding means inoperative, a connection between the throw-out mechanism and the jack controlling mechanism, said connection including two movable control members connected to the throw-out mechanism and the jack controlling mechanism respectively, a coupling adapted to lock the two members together so that operation of one results in operation of the other, operator controlled means for disconnecting said two members and then moving the member connected to the throw-out mechanism so as to render the strand feeding means inoperative, and means for locking the last mentioned member after it has been so moved by the operator controlled means.

14. In a fastening inserting machine, the combination with a work supporting jack movable into and out of an operative position, jack controlling mechanism, and mechanism for presenting a strand of fastening material, the latter mechanism including a strand supporting reel and strand feeding means, of a throw-out mechanism for rendering the strand feeding means inoperative, a connection between the throw-out mechanism and the jack controlling mechanism, said connection including two movable control members connected to the throw-out mechanism and the jack controlling mechanism respectively, a coupling adapted to lock the two members together so that operation of one results in operation of the other, operator controlled means for disconnecting said two members and then moving them with relation to each other to render the strand feeding means inoperative while leaving the jack controlling mechanism operative, and means for thereafter locking the operator controlled means and said members.

15. In a fastening inserting machine, the combination with a work supporting jack, jack controlling mechanism, a plunger for operating fastening inserting mechanism, and mechanism for feeding a strand of fastening material, of control mechanism comprising two rotatable members normally connected together, a strand feed throw-out mechanism, a connection between

one of said members and the throw-out mechanism, a connection between the other of said members and the jack controlling mechanism, and operator controlled means movable in one direction to disconnect said members from each other, the said means being movable in a second direction to rotate said members with relation to each other so as to operate the throw-out mechanism and then being movable in a third direction to render the plunger for fastening inserting mechanism inoperative.

16. In a fastening inserting machine, the combination with a work supporting jack, jack controlling mechanism, a plunger for operating fastening inserting mechanism, and mechanism for feeding a strand of fastening material, of control mechanism comprising two rotatable members normally connected together, a strand feed throw-out mechanism, a connection between one of said members and the throw-out mechanism, a connection between the other of said members and the jack controlling mechanism, operator controlled means movable in one direction to disconnect said members from each other, the said means being movable in a second direction to rotate said members with relation to each other so as to operate the throw-out mechanism and then being movable in a third direction to render the plunger for fastening inserting mechanism inoperative, and means for thereafter locking the operator controlled means and said members.

17. In a fastening inserting machine, the combination with a work supporting jack, jack controlling mechanism, a plunger for operating fastening inserting mechanism, and mechanism for feeding a strand of fastening material, of control mechanism comprising two normally connected members rotatable about a common axis, a strand feed throw-out mechanism, a connection between one of said members and the throw-out mechanism, a connection between the other of said members and the jack controlling mechanism, and operator controlled means rotatable about and movable in the direction of said axis, said means being adapted on axial movement in one direction to disconnect said members from each other, and being adapted on rotation to rotate said members with relation to each other so as to operate the throw-out mechanism, and also being adapted on axial movement in the opposite direction to render the plunger for fastening inserting mechanism inoperative.

18. In a fastening inserting machine, the combination with a work supporting jack, jack controlling mechanism, a plunger for operating

fastening inserting mechanism, and mechanism for feeding a strand of fastening material, of control mechanism comprising two normally connected members rotatable about a common axis, a strand feed throw-out mechanism, a connection between one of said members and the throw-out mechanism, a connection between the other of said members and the jack controlling mechanism, and operator controlled means rotatable about and movable in the direction of said axis, said means being adapted on axial movement in one direction to disconnect said members from each other, and being adapted on rotation to rotate said members with relation to each other so as to operate the throw-out mechanism, and also being adapted on axial movement in the opposite direction to reconnect said members and to render the plunger for fastening inserting mechanism inoperative.

19. In a fastening inserting machine, the combination with a work supporting jack, jack controlling mechanism, a plunger for operating fastening inserting mechanism, and mechanism for feeding a strand of fastening material, of control mechanism comprising two normally connected members rotatable about a common axis, a strand feed throw-out mechanism, a connection between one of said members and the throw-out mechanism, a connection between the other of said members and the jack controlling mechanism, operator controlled means rotatable about and movable in the direction of said axis, said means being adapted on axial movement in one direction to disconnect said members from each other, and being adapted on rotation to rotate said members with relation to each other so as to operate the throw-out mechanism, and also being adapted on axial movement in the opposite direction to reconnect said members and to render the plunger for fastening inserting mechanism inoperative, and means for thereafter locking the operator controlled means and said members.
